ATTORNEY

UNITED STATES PATENT OFFICE.

WALTER W. ROCKWOOD, OF CHICAGO, ILLINOIS, ASSIGNOR OF ONE-HALF TO ADA R. MELLISH, OF CHICAGO, ILLINOIS.

PAINTING APPARATUS.

Application filed May 23, 1927. Serial No. 193,580.

This invention relates to certain novel improvements in painting apparatus and more particularly to a novel construction for a booth in which articles are surfaced by means of a so-called spray gun.

In the prior art, spray booths have been constructed in which means was provided for moving air through the booth and this means was usually located so that the horizontal plane in which it operated was fixed. It is therefore the salient object of my invention to provide a spray booth in which the air moving means may be mounted at various levels.

A further object of the invention is to provide a spray booth of the type described which will be simple in construction and economical to manufacture.

Other objects will appear hereinafter.

The invention consists in the novel combination and arrangement of parts to be hereinafter described and claimed.

The invention will be best understood by reference to the accompanying drawings showing the preferred form of construction and in which:

The preferred embodiment of my invention is illustrated in perspective elevation.

In order to carry out the objects of my invention, I provide a booth 10 which is preferably constructed of sheet metal. The sides and top and bottom of this booth are preferably constructed of flat sheets of suitable metal and are fastened together in any approved or desired manner.

One end of the booth is open and the wall of the booth opposite this open end is provided with a construction which will now be described in detail. Relatively narrow strips 40 of sheet metal 11 and 12 are attached to the side walls and secured to the inner edges of these strips are sections 13 and 14 of so-called angle iron. Preferably this angle iron is of the right angular type and one portion thereof is suitably secured to the strips 11 and 12 in such a manner that the portions thereof which extend at right angles to the portions secured to the sections 11 and 12 will be in alignment with the edges of these sections, thus providing an open space therebetween.

Mounted so as to close the open space be-

tween the angle irons 13 and 14 are a plurality of removable panels such as 15, 16 and 17. The magnitude of these panels is preferably such that their widths will embody a fixed relation; for example, in the present instance, the panel 15 is three times the width of the panel 17, and the panel 16 is twice the width of the panel 17. These panels embody lip portions which extend at right angles to the surface of the panel and which are adapted to be brought into engagement with the angle irons 13 and 14. Suitable aligned openings are provided in the lip portions of the panels and the angle irons and detachable securing elements such as the bolt and nut constructions 18 extend through these openings so as to secure the panels in position.

As can be seen by referring to the drawings, the panels 15, 16 and 17 do not entirely close the opening between the angle irons 13 and 14. The remainder of this opening is closed by one side of a housing 19. In the portion of the housing 19 in juxtaposition to the booth 10, an exhaust fan 20 is provided. Adapted to have communication with the interior of the housing 19 preferably opposite the exhaust fan 20 is a conduit 21. This conduit 21 embodies an elbow construction 22 so that a portion of said conduit shall extend vertically. The vertically extending portion of the conduit 21 embodies a plurality of sections 23, 24 and 25. The section 23 is adapted to be arranged so that it can be slid into the section 24 and the section 24 is adapted to be arranged so that it can be slid into the section 25. This construction provides a telescopic arrangement for the conduit which serves a purpose to be brought forth presently.

As is well understood in the art, articles of various sizes and descriptions are surfaced or painted in spray booths by means of a so-called spray gun. It is apparent that if a large heavy casting is to be sprayed it would be advantageous to mount this casting on the floor of the booth in order that the operator would not be required to lift it onto a table. However, if smaller and easily handled pieces were to be sprayed it would be advantageous to locate these articles on a table. Further, if desired, small articles might be

suspended from the top of the cabinet in order that they might be surfaced or painted. From the foregoing, it is apparent that the spraying is carried on at various levels 5 in the booth. As is well understood, minute particles of the material being applied to the articles (such material being paint, enamel, and similar finishes or sand, in the case of sand-blasting) are suspended in free condition 10 in the housing. These particles are thrown off by the force of the impingement between the material and the article. It is readily apparent that it is highly advantageous to remove these particles from the 15 housing, both from a standpoint of convenience to the operator and to prevent their settling on articles within the housing and on the housing itself. In order to accomplish this, air moving means such as the exhaust fan 20 are provided.

As has been brought out in the preceding paragraph, articles of various sizes and descriptions are adapted to be surfaced in the booth. It is apparent that if a large article 25 is being surfaced, which is located on the floor of the booth, it will be advantageous to have the fan 20 located in the position indicated in the drawings, for the air movement will be greatest in the horizontal plane 30 in alignment with the fan. However, if a smaller size article is to be surfaced, which is to be positioned on a table during the surfacing, it will be advantageous to have the fan mounted at a higher level. In order 35 to accomplish this, the removable panel construction heretofore described is provided. When it is desired to move the fan upwardly a certain distance the panel or panels which represent the distance desired 40 to be moved are removed. Then the means which secure the housing 19 to the angle irons 13 and 14 are removed and the housing 19 is moved upwardly until the upper surface thereof is in engagement with the 45 panels remaining at the top which, it will be understood, are arranged so that they will close the upper portion of the opening between the angle irons. When the housing 19 is secured in this position the removed 50 panels are then inserted below said housing and the device is then ready for operation.

From the foregoing, It is apparent that I have provided a spray booth construction which is such that the air removing means 55 may be mounted on a horizontal level with the article being surfaced and therefore the force of air removal will be greatest at the point where it is most needed.

While I have illustrated and described 60 the preferred form of construction for carrying my invention into effect, this is capable of variation and modification, without departing from the spirit of the invention. I, therefore, do not wish to be limited to the precise details of construction set forth,

but desire to avail myself of such variations and modifications as come within the scope of the appended claims.

Having thus described my invention, what I claim as new and desire to protect 70 by Letters Patent is:

1. A spray booth having an open side, the wall of said booth opposite said open side being closed by removable panels and one side of a housing, a fan mounted in the wall 75 of said housing that is juxtaposed to said booth, a conduit in communication with said housing, said panels, housing, and conduit, being arranged so that said fan may be mounted at variable horizontal levels. 80

2. A spray booth having oppositely disposed open sides, a plurality of interchangeable members forming a partial closure for one of said open sides, and an exhaust fan housing adapted to co-act with said members to complete the closure of said side. 85

3. A spray booth having oppositely disposed open sides, a plurality of interchangeable members forming a partial closure for one of said open sides, and an exhaust fan 90 housing adapted to co-act with said members to complete the closure of said side, said housing being adapted for interchangeable relation with said members.

4. A spray booth having oppositely disposed open sides, a plurality of interchangeable members forming a partial closure for one of said open sides, and an exhaust fan housing adapted to co-act with said members to complete the closure of said side, a conduit adapted for communication with said housing embodying a telescopically arranged vertically extending portion, said conduit telescoping as said housing is interchanged with said members. 95

5. A spray booth having an open side, a plurality of interchangeable panels adapted to partially close said open side, and exhausting means embodying portions co-acting with said panels to complete the closure of said 100 open side.

6. A spray booth including a sheet metal enclosure having oppositely disposed open sides, relatively narrow strips disposed on one of said open sides in juxtaposition to the side walls of said enclosure, a plurality of correlated panels disposed to partially close the space between said strips, said panels being detachably secured to said strips, and a housing having a side disposed 115 in said space adapted to co-act with said panels to complete the closure of said space, said housing being detachably secured to said strips and embodying means for creating a draft through said enclosure. 120

7. A spray booth including a sheet metal enclosure having oppositely disposed open sides, relatively narrow strips disposed on one of said open sides in juxtaposition to the side walls of said enclosure, a plurality 130

of correlated panels disposed to partially close the space between said strips, said panels being detachably secured to said strips, and a housing having a side disposed in said space adapted to co-act with said panels to complete the closure of said space, said housing being detachably secured to said strips and embodying means for creat-

ing a draft through said enclosure, a conduit in communication with said housing, 10 said conduit embodying a vertically disposed portion including telescopically arranged sections, said sections telescoping as said housing is interchanged with said panels.

In testimony whereof I affix my signature.

WALTER W. ROCKWOOD.
